[57] CLAIM

The ornamental design for a beach cart, as shown and described.

DESCRIPTION

FIG. 1 is a front, right side and top environmental perspective view of a beach cart showing my new design, the portion of the figure shown in broken lines representing users of the design and other equipment, and forming no part of the claimed design;

FIG. 2 is a top plan view thereof;

FIG. 3 is a right side elevational view thereof, the left side elevational view being a mirror image;

FIG. 4 is a front elevational view thereof;

FIG. 5 is a rear elevational view thereof; and,

FIG. 6 is a bottom plan view thereof.

FIG. 1

FIG. 2

FIG. 3

FIG. 4

FIG. 5

FIG. 6
